UNITED STATES PATENT OFFICE.

LOUIS OEDELL AND ARTHUR BELL, OF WATERBURY, CONNECTICUT, ASSIGNEES TO
WATERBURY CLOCK CO., OF WATERBURY, CONNECTICUT, A CORPORATION.

WATCH.

Application filed May 15, 1922. Serial No. 560,905.

To all whom it may concern:

Be it known that we, LOUIS OEDELL and ARTHUR BELL, citizens of the United States, residing at Waterbury, in the county of New Haven and State of Connecticut, have invented a new and useful Improvement in Watches; and we do hereby declare the following, when taken in connection with the accompanying drawings and the characters 10 of reference marked thereon, to be a full, clear, and exact description of the same, and which said drawings constitute part of this application, and represent, in—

Fig. 1 a view in front elevation of the 15 front movement-plate of a watch constructed in accordance with our invention.

Fig. 2 a rear view thereof.

Fig. 3 an enlarged sectional view thereof on the line 3—3 of Fig. 1.

20 Fig. 4 a view in front elevation of the front movement-plate before the bridge has been applied thereto and riveted in place.

Fig. 5 an enlarged broken sectional view on the line 5—5 of Fig. 4, showing one of 25 the rivets formed by upsetting the plate.

Fig. 6 a detached plan view of the bridge.

Fig. 7 a broken sectional view of such a punch and die as may be used in producing our improved movement-plate.

30 Our invention relates to an improvement in watch-movements, the object being to provide simple, reliable, convenient and accurate means for securing bridges to the plates thereof at the minimum outlay for time and 35 labor.

With these ends in view, our invention consists in certain details of construction as will be hereinafter described and pointed out in the claim.

40 In carrying out our invention, as herein shown, the front movement-plate 10 is formed at one side of its center with a large, circular clearance-opening 11, designed, in the present instance, to provide clearance for 45 the third wheel, not shown, of the movement-train. Near the edges of the said clearance-opening 11 and at diametrically opposite points, the said plate 10 is struck from rear to front, between punches 12, with slightly 50 tapered ends, and dies 13, to form two integral, cylindrical rivets 14, parallel with each

other and standing at a right angle to the plane of the plate, and resulting in the production in the rear face of the plate of circular recesses 15 concentric with but larger than the rivets 14, and small, relatively deep co-axial recesses 16 leading out of the bottoms of the recesses 15, and as shown, extending slightly into the bases of the rivets 14, the recesses 16 being produced by small, 60 slightly tapered concentric pins 17 projecting from the ends of the punches 12.

The integral rivets 14 having been produced as described, a light, sheet-metal bridge 18 is applied to the outer face of the 65 plate 10, over the clearance-opening 11 therein, the ends of the bridge being set inward, as at 19, and formed with perforations 20 adapted in diameter to snugly receive the rivets 14, which are made long enough to be 70 headed down, or otherwise swaged, upon the outer faces of the ends 19 of the bridge, as shown in Fig. 3, in which the ends of the rivets have a conical depression 21 produced by the action of a spreading or swaging 75 prick-point. The bridge as thus mounted is not only permanently but accurately secured in place, and with far more convenience and ease and with the employment of less time than by the ordinary method of employing 80 for the purpose small, independent rivets, which are difficult to handle and position, and to maintain in position while being swaged.

After the bridge has been secured in place, 85 it is drilled as required for the reception of the ends of the arbors for which it is designed to provide a bearing. As shown, it is formed with a central perforation 22 for a pinion of the third wheel and with a perforation 23 for the reception of a pinion of the 90 fourth wheel.

We claim:

In a watch movement, the combination with a movement-plate formed with a clearance-opening, with two integral rivets located adjacent to opposite edges of the said opening and projecting from the outer face of the plate, with two recesses formed in its inner face and respectively co-axial with but 100 larger than the said rivets and with two recesses respectively co-axial with the said

rivets, smaller than the same and leading out
of the bottoms of the recesses first men-
tioned; of a bridge applied to the said plate
over the said clearance-opening and formed
5 at its ends with perforations for the recep-
tion of the rivets, which are headed down
upon the ends of the bridge.

In testimony whereof, we have signed this

specification in the presence of two subscrib-
ing witnesses.

LOUIS OEDELL.
ARTHUR BELL.
